200,138

COMBINED SCALP AND CHIN VIBRATOR

Roy G. Steele, 2720 E. 13th Ave., Denver, Colo.

Filed May 14, 1964, Ser. No. 79,986

Term of patent 14 years

(Cl. D83—1)

FIG. 4

FIG. 5

FIG. 6

FIG. 1 is an elevational side view of a combined scalp and chin vibrator, showing my new design.

FIG. 2 is an elevational side view of the opposite side thereof.

FIG. 3 is an elevational front view thereof.

FIG. 4 is an elevational rear view thereof.

FIG. 5 is a top plan view and FIG. 6 is a bottom view thereof.

The dominant features of my design reside in the portions shown in full lines.

I claim:

The ornamental design for a combined scalp and chin vibrator, as shown and described.
